POISON SPRAYING MACHINE

Charles Kosik, Tavener, Tex., assignor of one-half
to Jesse James Duckett, El Camp, Tex.

Application February 23, 1939, Serial No. 258,107

1 Claim. (Cl. 259—95)

The present invention relates to new and useful improvements in poison spraying machines and has for one of its important objects to provide, in a manner as hereinafter set forth, a device of this character comprising pumping means of a novel construction and arrangement for discharging the poison under pressure.

Another very important object of the invention is to provide a machine of the aforementioned character comprising unique means for keeping the poison composition thoroughly mixed while the machine is in operation.

Still another important object of the invention is to provide a poison spraying machine which is adapted to be mounted for operation on a conventional tractor and driven from the usual power take-off thereof.

Other objects of the invention are to provide a poison spraying machine of the character described which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is an elevational view of a poison spraying machine constructed in accordance with the present invention.

Figure 2 is a top plan view thereof.

Figure 3 is a vertical sectional view through the machine, showing the gears of the pump exposed.

Figure 4 is a view in vertical section through the lower portion of the delivery pipe.

Figure 5 is a view in horizontal section, taken substantially on the line 5—5 of Fig. 4.

Figure 6 is a horizontal sectional view, taken substantially on the line 6—6 of Fig. 4.

Figure 7 is a vertical sectional view through the return pipe.

Figure 8 is a horizontal sectional view, taken substantially on the line 8—8 of Fig. 7.

Referring now to the drawings in detail, it will be seen that the embodiment of the invention which has been illustrated comprises a tank 1 for the reception of the poison, said tank being of any suitable capacity and material. The top 2 of the tank 1 is provided with a suitable closure 3 which permits the poison to be placed in said tank. It may be well to here state that the

tank 1 is adapted to be mounted on the rear end portion of a conventional tractor adjacent the power take-off thereof.

Mounted on the top 2 of the tank 1 is a gear type pump 4 which is actuated by a pulley 5. The pulley 5 is to be connected by an endless drive belt to the aforementioned power take-off of the tractor. Of course, any other suitable source of power may be used. Also, the ratio of the pulley 5 relative to the power take-off pulley 10 may be as desired.

Extending downwardly from the pump 4 into the tank 1 to a point adjacent the bottom 6 of said tank is a delivery pipe 7. As illustrated to advantage in Fig. 4 of the drawings, the lower portion of the delivery pipe 7 is perforated, as at 8, and enclosed in a screen 9. Above the perforations 8 a check valve 10 is provided in the pipe 7. Also mounted on the lower portion of the pipe 7 is a jacket 11 which encloses the screen 9 in spaced concentric relation thereto.

As will be readily seen, the top of the pump 4 is the outlet side thereof and connected thereto is a discharge conduit 12 which is controlled by a valve 13. Mounted in the discharge conduit 12 ahead of the valve 13 is a removable plug 14 which permits the pump 4 to be primed. Any suitable member and type of spray nozzles may be connected to the discharge conduit 12. Also communicating with the outlet side of the pump 4 is a pressure gauge 15. A cushioning chamber 16 is interposed between the pressure gauge 15 and the pump 4.

Connected to the discharge conduit 12 is a return pipe 17 which extends downwardly into the tank 1 to a point adjacent the bottom 6 thereof. Mounted on the lower end portion of the return pipe 17 is a seat 18 of substantially the shape shown to advantage in Fig. 8 of the drawings. The reference numeral 19 designates a control valve for the return pipe 17 which is engageable with the seat 18. The valve 19 is mounted on the lower end of the rod 20 which extends vertically through the return pipe 17 and which is connected to a stem 21 which is threadedly mounted in a T 22 on the upper end of said pipe. The threaded stem 21 is provided with an operating wheel 23. A packing 24 is provided for the stem 21 for preventing leakage of the poison composition under pressure at this point.

It is thought that the operation of the device will be readily apparent from a consideration of the foregoing. Briefly, with the valves 13 and 19 adjusted as desired, the poison composition is drawn into the lower portion of the pipe

1 through the screen 9 from a point adjacent the bottom of the tank 1. The composition flows upwardly through the pipe 7, being elevated by the gear pump 4, and enters the discharge conduit 12 under pressure. A portion of this composition from the pump 4 flows through the discharge conduit 12 to the nozzle or nozzles. The rest of this poison from the pump 4 is returned to the tank 1 through the pipe 17 and is discharged adjacent the bottom 6 of said tank in a manner to stir and to thoroughly mix the composition in said tank. Through the medium of the valve 19 the proportion of the composition returning to the tank 1 may be regulated as desired, also the pressure of the composition at the nozzles controlled.

It is believed that the many advantages of a poison spraying machine constructed in accordance with the present invention will be readily understood and although a preferred embodiment of the device is as illustrated and described, it is to be understood that changes in the details of construction and in the combination and

arrangement of parts may be resorted to which will fall within the scope of the invention as claimed.

What is claimed is:

A spraying machine comprising a tank for the reception of material to be sprayed, a pump, a pipe connected with the inlet of the pump and extending into the tank to a point adjacent the bottom thereof, a return pipe extending into the tank from the discharge side of the pump for agitating the material in said tank the lower end of the return pipe having a star-shaped outlet port therein, a valve rod passing through the return pipe with its lower end extending through the port, a disk valve connected to said lower end for closing the port when the rod is raised, said valve being of much larger diameter than that of the port to act as a deflector when the rod is in lowered position to space the valve below the ported end of the return pipe and means at the upper end of the rod for raising and lowering the same.

CHARLES KOSIK.
